SHEET-TRANSFER MECHANISM FOR MULTICYLINDER PRESSES.

Application filed June 30, 1923. Serial No. 648,841.

Our invention relates to mechanism for controlling the transfer of the sheets from one cylinder to another in a multi-cylinder press of the sheet feed type, whether it be a 5 printing press, cutter and creaser or other form of press. The invention has to do more with the gripper mechanism though the present gripper mechanism makes possible certain modifications in the structural features 10 of the press.

Heretofore it has been customary to operate the transfer grippers on multi-cylinder presses by means of either sliding cams or sliding pins and it has also been customary to 15 operate the grippers on single color presses with sliding means. The movability of the gripper operating means resulted in some looseness or play in the parts, especially after they became worn, and this produced inaccuracies in the register of the press. In 20 multi-color presses or multi-impression presses these errors are cumulative and one object of the present invention is to avoid this in all presses and especially in multi-cylinder presses. In the present case the gripper operating members do not slide into 25 and out of position to actuate the grippers and therefore their positions may be fixed and unchanging, resulting in accurate register. By this we do not mean that every 30 member effecting the operation of the grippers necessarily has to be stationary but in the present case those members are stationary which can in any way affect the accuracy of 35 register. It will be apparent that in two revolution presses where a sheet is printed every two revolutions of the impression cylinders the grippers on the cylinders perform their complete functions once for every two 40 revolutions, and movable cams or pins have heretofore been used to operate the grippers on the transfer cylinder in order that they could be moved out of the way of the tym- 45 pans for every alternate revolution. We 50 have avoided the defects or imperfections of movable cams and pins by making the cams which control the initial opening and final closing of the grippers of the transfer cylinder on the sheet stationary and we provide 55 means for holding the grippers out of opera- 60 tive relation with the stationary cams at each alternate revolution of the impression cylinders.

In the fullest embodiment of our invention

not only are the transfer grippers held out of 55 operative relation with the stationary cams but they are turned completely within the peripheral line of the transfer cylinder and this feature is not only a decided advantage 60 in conjunction with stationary cams but it is susceptible of independent use for its individual advantages. Heretofore, the transfer cylinder of multi-color or multi-cylinder presses has generally been made smaller than 65 the impression cylinders and some even subdivision of the size of the latter, generally one half the diameter of the impression cylinders, in order that the transfer grippers on the second revolution of the impression cylinders would come opposite the openings of 70 the impression cylinders or escape the tympan surface to prevent destruction. This made it necessary to limit the size of the transfer cylinder generally to one half the size of the impression cylinders. This limited size results in less efficiency in the action 75 of the transfer grippers and the sheet is curved into a small circle, especially as in such constructions the sheet has to travel around with the transfer cylinder more than 80 one revolution of the latter.

In the present case the grippers on the transfer cylinder do not have to come opposite the impression cylinder openings at each alternate revolution of the impression cylinders and therefore the gripper devices place 85 no limitations on the size of the transfer cylinder. As a matter of preference we have made the transfer cylinder with a diameter equal to two-thirds the diameter of the impression cylinders, so that the transfer cylinder makes three complete revolutions while 90 the impression cylinders are making two revolutions. The sheet is therefore not curved in so small an arc on the transfer cylinder and instead of having to make two revolutions on this cylinder in order that the sheet may be fully taken from one cylinder 95 ready for transfer to the other, the sheet need only travel a little more than half way around on one revolution of the transfer cylinder between the time the leading edge leaves one impression cylinder and is taken by the next one, owing to the increased size 100 of the transfer cylinder. These advantages 105 flow from the use of our gripper mechanism as will appear.

Another broad feature of our invention is

the use of cams on the impression cylinders for placing certain of the cams which operate the grippers on the transfer cylinder, into and out of operative position. Other advantages will be apparent from the following detailed description of one embodiment of our invention.

In the drawings forming part of this application,

10 Figure 1 is a diagrammatic side elevation of a two revolution multi-cylinder printing press in conjunction with which we have applied our invention.

Figures 2, 3, 4 and 5 are enlarged end 15 elevations of the cylinders, showing the gripper devices in the different positions they assume in a complete cycle of operations, in some of which views some of the parts are omitted for simplicity of illustration, and to avoid unnecessary duplication,

Figure 6 is a similar view which also shows certain springs and cams for operating some of the parts, and

25 Figure 7 is a plan view.
25 In the drawings we have shown our invention applied to a two revolution press in which a sheet is printed at every second revolution and wherein the sheet receives two impressions on the same side while 30 passing through the press, though it will be apparent that the invention is not limited to this particular application. Herein we have shown one of the side frames 60 of the press, on which is mounted the feed board 61 and a delivery 62. Between these is arranged the rear or first impression cylinder 9 which first receives the sheet from the feed board, and below this is the rear or first plate cylinder 63 which carries the first 35 plate or form to operate on the sheet and it cooperates with the first impression cylinder 9 in making the first impression on the sheet. After the first impression has been made the sheet is taken from the impression cylinder 9 by the transfer cylinder 10 which then transfers the sheet to the second impression cylinder 11.

40 While traveling around with the latter the sheet receives a second impression from the 50 form or plate on the second plate cylinder 64 and then the sheet is taken from the latter cylinder by the delivery mechanism. Our present invention requires no change in the gripper mechanisms of the impression cylinders and therefore in so far as we have shown parts thereof they conform to present practice. As stated above, we have made the diameter of the transfer cylinder 10 equal to two thirds the diameter of the impression 55 cylinders 9, 11, and as all these cylinders are connected by a chain of gears in well known manner the transfer cylinder will make three complete revolutions while the impression cylinders are making two complete 60 revolutions. The impression operations take

place on each alternate revolution of the respective impression cylinders where the press is of the two revolution type as shown herein.

70 In Figure 2 we have shown the principal parts of our mechanism. In this view, 9 is the rear or first impression cylinder, referred to above, 10 is the transfer cylinder and 11 is the second impression cylinder looking at the same side of the press as in Figure 1. The sheet 26 has made a revolution with the impression cylinder 9 and has received the first impression from the form or plate on cylinder 63 and the sheet in this view is in the process of being transferred from the impression cylinder 9 to the transfer cylinder 10. At the instant shown by this view the leading edge of the sheet 26 is held against the tympan of the cylinder 9 by the gripper fingers 27 which are of usual construction. These are the grippers carried by the impression cylinder 9 and are here shown as having the usual crank arm 29 provided with a roller 30 which is actuated by the cam 31 which is moved laterally on the pins 32, 33 periodically into and out of the path of the roller 30 at alternate revolutions of the cylinder 9. At the instant illustrated in Figure 2 the gripper fingers 27 are about to be released from the edge of the sheet 26 to permit the sheet to transfer to the cylinder 10. The grippers 28 are mounted on the transfer cylinder 10 and in this view they have just closed on the edge of the sheet at the bight of the cylinders 9, 10, to grip the sheet against the transfer cylinder at or about the time the grippers 27 are released, so that the sheet will pass from the cylinder 9 to the cylinder 10.

100 The transfer grippers 28 are attached to the shaft 34 and they are operated primarily through the crank 35 attached to the shaft 34, which crank carries the roller 36, these last mentioned parts being arranged on the end of shaft 34 from which Figure 2 reads. On the opposite end of the shaft 34 there is a second crank 37 which carries a roller 38 and the cranks 35 and 37 are disposed approximately the angle shown in the drawings.

105 On the shaft 34 (as may be seen by reference to Figure 6) there is fixed a third crank 65 which has approximately the angular displacement relatively to cranks 35 and 37 as shown. There is a rod 39 having one end seated in a recess 66 in the transfer cylinder and the other end is pivoted to the free end of the crank 65. There is a coiled spring 67 surrounding this rod and compressed between the cylinder wall and the collar 68 adjustably fixed to the rod 39. The tendency of this spring 67 is to force the rod 39 to the right in Figure 6. This pressure will tend to turn the gripper shaft 34 and as the rod 39 is adapted to move to either side of the

axis of the shaft 34 the pressure of the spring 67 will tend to turn the shaft 34 clockwise or counter-clockwise according to which side of the axial line of shaft 34 the rod is directed. In the position shown in Figure 6 the spring 67 tends to hold the grippers 28 closed on the sheet as in Figure 2. It will be apparent that if the shaft 34 is turned in opposition to the spring 67 until the rod 39 passes to the other side of the axis of shaft 34 the spring will then have a tendency to turn the shaft 34 in the opposite direction and bring the rod 39 to the dotted line position 40 and this would retract the gripper fingers well within the peripheral line of the transfer cylinder.

Reverting to Figure 2 it will be seen that we have provided a stationary bracket 49 on the side of the press on which is rigidly attached the two stationary cams 41 and 45 only the outer surface of which perform any function in the construction shown. These are the only cams associated with the transfer cylinder which have any effect on the accuracy of the register and as they can be rigidly mounted they will always operate the grippers 28 at the same points. In Figure 2 the roller 36 is just leaving the surface of the cam 41 so that the shaft 34 is being rotated by the pressure of spring 67 which tends to move this shaft counterclockwise and thus press the grippers 28 against the sheet 26.

In this same view we have shown the cam 44 associated with the second impression cylinder 11 and sliding on the pins 44^a and this cam, which is of usual construction, corresponds with the cam 31 but operates the grippers 42 on cylinder 11.

When the parts have advanced so that the transfer cylinder has made slightly more than one half revolution the condition of the parts will then be as shown in Figure 3. The transfer grippers have moved past the bight of the cylinders 10 and 11 and just as they are moving away from the bight, the roller 36 will have engaged the stationary cam 45 and as the cylinder 10 continues to revolve, the cam 45 operates on the roller 36 and crank 35 to rotate the shaft 34 clockwise in this view and this will release the grippers 28 from the sheet. While the leading edge of the sheet was at the bight of the cylinders 10, 11 and just as the grippers 28 were about to release the sheet the grippers 42 on the cylinder 11 were closed by means controlled by the cam 44 in the usual manner and the sheet has therefore commenced to transfer from cylinder 10 to cylinder 11 when the parts arrive at the positions shown in Figure 3. In Figure 3 the cam 45 has operated on the roller 36 to turn the shaft 34 clockwise until the spring 67 would tend to force the crank 65 over against the stop pin 69 with a slam. To

control this action we have provided a cam 46 which is secured upon an arm 47 which swings from the center 48. In Figure 3 this arm is shown held down so that the cam 46 is in the path of the roller 38. The cam 45 therefore acts on the roller 36 to turn the shaft 34 and open the grippers 28, and about this time the rod 39 has passed the center of shaft 34, whereupon the roller 38 on the crank arm 37 is pressed against the cam 46 and the latter will prevent sudden turning of the shaft 34 by the spring 67. As the cylinder 10 continues its motion the roller 36 will pass beyond the cam 45 and the roller 38 will ride off the cam 46, so that the shaft 34 will be gradually turned, first by the cam 45, then by the spring 39, controlled by the cam 46, and when the roller 38 passes off the cam 46 the grippers 28 will have been moved completely inside the periphery of the cylinder 10 so that they can pass any portion of the impression cylinders.

In Figure 4 the parts are shown in the positions that obtain after the transfer cylinder has made about a quarter turn from that of Figure 3. The rollers 36 and 38 have left the cams 45, 46 and the grippers are held fully retracted by the spring 67. The arm 47 has now been swung so that the cam 46 is out of the path of the roller 38.

The cam 53 corresponds with the cam 46 being oppositely disposed, and it is mounted on an arm 54 that swings from the center 55. In Figure 4 this arm 54 is swung out so that the cam 53 is also out of the path of the roller 38. The roller 36 is now so held that neither of the stationary cams 41, 45 will act upon this roller. While the gripper mechanism is in this position the cylinder 10 will make two complete revolutions, the grippers 28 being held retracted all this time and being free to pass the impression cylinders at any point.

When the cylinder 10 has made two revolutions from the position of Figure 4 the parts will then appear as shown in Figure 5. Here the arm 54 has been swung down so that the cam 53 is now in the path of the roller 38. As the roller 38 moves along this cam 53 the shaft 34 is turned counter-clockwise to start the closing of the grippers. Before, or at the time the rod 39 crosses the axis of the shaft 34 the roller 36 is in position to engage the fixed cam 41 and as the cylinder 10 turns further, the rod 39 will pass the axis of the shaft 34 and the spring 67 will continue the closing action of the grippers 28, restrained from sudden action by the cam 41 acting on roller 36, and when the grippers arrive at the bight of the cylinders 9, 10, they will have been fully closed on the sheet. A complete cycle of operation has been traced and the same functions will be repeated at each succeeding cycle.

There is a spring 52 having one end con-

ected to some stationary part of the press, such as the frame members 70 (Fig. 6) and the other end is connected to the arm 47 which carries the cam 46. This spring tends to draw over the arm 47 to the left in Figure 6. The arm 47 is moved in the opposite direction by means of a cam 51 mounted on the impression cylinder 11. As the latter makes a revolution the arm 47 is moved back and forth to place the cam 46 into and out of operative relation to the roller 38. There is a similar spring 58 arranged to draw over the arm 54 to move the cam 53 to the right in Figure 6 or out of the path of the roller 38. The cam 57 on the cylinder 9 acts on the roller 56 on the end of this arm to move it to the left in Figure 6. At each revolution of the cylinder 9 the cam 53 is moved into and out of the path of the roller 38 to bring about the results described above.

During the other revolution of the cylinder the cam 57 forces the cam 53 into position just the same, but at that time the roller 38 is nearly diagonally opposite from the position shown in Figure 5. Therefore, that is an idle stroke of the cam.

It will be noted that the cams 41, 45 are the only ones which have any effect on the accuracy of the register so far as the transfer cylinder is concerned and these may be fixed instead of sliding so that they are invariable in their operation on the grippers. The cams 46, 53 on the other hand, do not affect the accuracy of the register and therefore they can be movable as is shown.

Operation.—The operation has been set forth in conjunction with the construction but we will refer briefly to the sequence of these operations. The sheet is taken from the feed board by the first impression cylinder, the sheet makes a revolution with this cylinder at the same time receiving the first impression. As the sheet passes the transfer cylinder the grippers on the latter are turned back within the cylinder and do not touch the sheet. After the first impression is complete the cylinder 9 comes around to the position shown in Figure 2. Here the sheet is transferred from the cylinder 9 to the transfer cylinder 10 by means operated through stationary cams. The sheet travels a partial revolution with the transfer cylinder, about a half revolution, and then the transfer grippers are opened by means of the stationary cam 45 and the sheet is taken by the second impression cylinder 11. As the transfer cylinder proceeds beyond the point where it transfers the sheet to cylinder 11 its grippers are opened way into the cylinder and away from the path of the impression cylinders; and with the grippers in this condition the transfer cylinder makes two complete revolutions and the operations are repeated.

We do not wish to be understood as limiting our invention to any set of proportions. It is not necessary but only preferable that the diameter of the transfer cylinder be two thirds the diameter of the impression cylinder and of course if this proportion is not used then the other factors are modified accordingly.

Having described our invention, what we claim is:

1. In a press the combination of impression cylinders and a transfer cylinder, grippers for the sheets on said cylinders and means for operating the grippers of the transfer cylinder, comprising a stationary member for controlling the closing of the transfer cylinder grippers, and means for automatically placing a member of said grippers into and out of the path of said stationary member whereby the latter will control the closing of the grippers of said transfer cylinder.

2. In a press the combination of impression cylinders and a transfer cylinder, grippers for the sheets on said cylinders and means for operating the grippers of the transfer cylinder, comprising a stationary member for opening the transfer cylinder grippers, and means for automatically placing a portion of said grippers in position to be acted upon by said stationary member whereby the latter will, upon revolution of the transfer cylinder, open the grippers thereof.

3. In a press the combination of impression cylinders and a transfer cylinder, grippers on said cylinders for the sheets, and means for operating the grippers of the transfer cylinder comprising stationary members one of which is adapted to control the closing of said grippers and the other adapted to open said grippers, and means for automatically placing said grippers into and out of position to be actuated by said stationary members upon the revolution of said transfer cylinder.

4. In a press the combination of impression cylinders and a transfer cylinder, grippers on the cylinders for the sheets, and means for operating the grippers of the transfer cylinder comprising a stationary member for controlling the closing of the transfer cylinder grippers, and means for automatically placing said grippers periodically into and out of condition to be operated by said stationary member.

5. In a press the combination of impression cylinders and a transfer cylinder, grippers on said cylinders for the sheets, and means for operating the transfer cylinder grippers, comprising stationary means for opening said grippers and means for automatically placing said grippers periodically into and out of condition to be operated by said stationary means.

6. In a press the combination of impression cylinders and a transfer cylinder, grippers on said cylinders for the sheets, and means for operating the transfer cylinder grippers, comprising stationary means for actuating said grippers and means for automatically placing said grippers into condition to be operated by said stationary means and adapted to place said grippers out of operative condition during at least one complete revolution of the transfer cylinder.
7. In a press the combination of impression cylinders and a transfer cylinder, grippers on said cylinders for the sheet, means for actuating the transfer cylinder grippers and means for automatically placing said grippers into position to be actuated by their actuating means and adapted to move said grippers out of condition for actuation, by moving them entirely within the peripheral line of said transfer cylinder.
8. In a press the combination of impression cylinders and a transfer cylinder having grippers for the sheets, and means for actuating the grippers on the transfer cylinder, comprising stationary cams for opening and controlling the closing of said grippers, movable cams for placing said grippers periodically into and out of condition to be operated by said stationary cams, and means for operating said movable cams.
9. In a press the combination of impression cylinders and a transfer cylinder, having grippers for the sheets, means for actuating the grippers on the transfer cylinder, movable means for placing said grippers automatically into and out of condition to be operated by said actuating means, and means movable with the impression cylinders for operating said means for placing said grippers into and out of operative condition.
10. In a press the combination of impression cylinders and a transfer cylinder, having grippers for the sheets, stationary cams for controlling the grippers of the transfer cylinder, a movable cam for placing said grippers into position to be acted on by a stationary cam, and a cam movable with an impression cylinder for placing said movable cam into position.
11. In a press the combination of impression cylinders and a transfer cylinder having grippers for the sheet, a shaft on which the transfer grippers are mounted, having a plurality of arms disposed at an angle to each other, a stationary cam acting on one of said arms to control the closing of the grippers of said transfer cylinder, and a movable cam acting on another of said arms to place said first arm into operative relation to said stationary cam.
12. In a press the combination of impression cylinders and a transfer cylinder hav-
- ing grippers for the sheet, a shaft on which the transfer grippers are mounted, having a plurality of arms, a stationary cam acting on one of said arms to control the closing of the grippers of said transfer cylinder, a movable cam acting on another of said arms to place said first arm into operative relation to said stationary cam, and a cam moving with the impression cylinders for placing said movable cam into operative relation to said second arm.
13. In a press the combination of impression cylinders and a transfer cylinder, said transfer cylinder having grippers mounted on a shaft, said shaft having a plurality of arms, a spring device operating on one of said arms and arranged to operate on either side of a dead center to turn said shaft in opposite directions, a stationary cam acting on another of said arms to control the closing of the transfer cylinder grippers, a movable cam mounted on a swinging arm, and means for operating said swinging arm to move said movable cam into and out of operative relation to another of said arms upon said shaft.
14. In a press the combination of an impression cylinder and a transfer cylinder having grippers for the sheet, a shaft on which the transfer grippers are mounted, said shaft having means for co-operating with a cam, a stationary cam for actuating said latter means to cause the opening of the grippers, and a movable cam for regulating said means.
15. In a press the combination of an impression cylinder and a transfer cylinder, grippers on said cylinders for the sheets, means for operating the grippers of the transfer cylinder, comprising stationary members adapted to control the closing and cause the opening of said grippers, and means for automatically and periodically placing said grippers into and out of position to be actuated by said stationary members.
16. In a press the combination of impression cylinders and a transfer cylinder, said transfer cylinder having grippers mounted on a shaft, said shaft having a plurality of arms, a spring device acting on one of said arms to operate on either side of a dead center to turn said shaft in opposite directions, stationary cams acting on another of said arms, movable cams, and means for operating them whereby one of said movable cams is caused to act on one of said arms to turn said shaft and the other operating on said arm to restrain sudden turning of said shaft under the action of said spring device.

Signed at New London, in the county of New London and State of Connecticut this 31st day of March, 1923.

THOMAS L. PERRY.
FRED S. ENGLISH.
